UNITED STATES PATENT OFFICE.

JOHN C. HEBDEN, OF PROVIDENCE, RHODE ISLAND, AND FREDERICK H. DANIELL, OF FRANKLIN, NEW HAMPSHIRE; MARY B. DANIELL, OF FRANKLIN, NEW HAMPSHIRE, EXECUTRIX OF SAID FREDERICK H. DANIELL, DECEASED.

METHOD OF DYEING YARN.

996,761.

Specification of Letters Patent.

Patented July 4, 1911.

Application filed April 16, 1908. Serial No. 427,379.

To all whom it may concern:

Be it known that we, JOHN C. HEBDEN and FREDERICK H. DANIELL, citizens of the United States, residing at Providence, in 5 the county of Providence and State of Rhode Island, and at Franklin, county of Merrimack, State of New Hampshire, have invented certain new and useful Improvements in Methods of Dyeing Yarn, of which 10 the following is a specification.

Our invention relates to the art of dyeing yarn in the cop or package, and consists of improvements in the method of preparing, arranging and treating the cops in 15 dyeing or similar processes, such as oxidizing, mordanting, bleaching, steaming, scouring, drying, washing, or the like.

The invention is fully set forth in the following specification, illustrated by the accompanying drawings, in which—

Figure 1, is a sectional view showing the preferred form of cop, and the tube for supporting the same; Fig. 2, a view illustrating one method of arranging a plurality of cops under compression, for subjection to the dyeing or other process; Figs. 3 and 4, views showing other methods of performing the same function.

In Fig. 1, is shown a cop or package of 30 yarn A of cylindrical form, wound on a tube B, which is longitudinally contractible under pressure. The preferred form of cop-tube is shown and particularly described in an application for patent, Serial 35 No. 417,419, filed Feb. 24th, 1908, and consists, essentially, of a flexible sleeve b, of reticulated fabric, supported and distended in tubular form by a helical coil of wire c, or by an equivalent skeleton or ribbed 40 framework which will allow the tube to be contracted along its axis. This form of tube is particularly adapted for cops wound to a large diameter and capable of containing a maximum quantity of yarn compacted in a minimum space and susceptible 45 of being freely unwound in the various transferring processes of manufacture for which the material is intended.

It is advantageous to dye yarn in commercial packages of large volume, in order 50 that the yarn may be economically handled in shipping and in transferring it in manufacturing processes, such as twisting, knitting, warping, etc. It will be obvious that

it is desirable to have the yarn in as long 55 lengths as possible, to avoid tying it up in the making of thread or fabric, and the present form of cop provides a much greater length than in skeins, hanks, chains or mule cops.

The usual method is to dye the yarn in the skein, hank or chain, and, in some cases, it has been dyed in the mule cop; but heretofore, attempts to dye yarn in packages of considerable size have not been entirely successful. It has been found difficult to secure an even and thorough permeation of the dye liquor throughout the whole mass, which is necessary to secure an even color, and it has also been found impossible to retain the cop in its original conformation, after the dyeing, so that the yarn can be subsequently unwound without snarling or breaking.

We have discovered a method of supporting the yarn in cops and arranging the cops under compression so that the yarn mass is of uniform density throughout, and presents a sufficiently large area on the inner surface to facilitate a thorough penetration. The liquor or gas is forced through the cop from the interior opening, and in some cases withdrawn again back through the yarn, by means of suction, or it might be forced through from the outside of the 80 cop.

It is desirable to dye a large number of cops at one time, and in order to present an even resistance to the penetration of the liquor throughout all the cops the yarn is 90 compressed into one solid mass. The packages are arranged end for end, with their central openings alining, and pressed together into one continuous tubular mass with a central opening. For convenience in handling it is preferable to arrange the cops in units, with from three to six cops in each unit. A number of units is then placed in the dyeing chamber, as many as it will accommodate, and all the cops subjected to the 95 liquor at one time.

Fig. 2, shows one method of supporting the cops A—A, etc., in a unit of three, with a perforated pipe P extending through their openings. At one end of the pipe a flange or head f is held by a collar g, screwed on to the pipe, or fastened in any suitable manner, and at the opposite end, the flange f² is adapted

2

to be adjusted along the pipe and pressed against the end of the end cop by means of the hand nut g^2 , or through an equivalent device. The cops are placed on the pipe and 5 pressed together, so as to leave no interstices between their ends, the cop-tubes B contracting longitudinally under pressure as the cops are compressed. The ends of the pipe are then connected with suitable valves in the 10 dyeing chamber and the liquor forced into the pipe, from which it escapes through the perforations p and flows between the coils c of the tubes, through the sleeves b and into the yarn mass. One system of injecting the 15 liquor is to close the valve at one end of the pipe and force it in at the other end. After a sufficient flow has been secured, the inlet valve is closed and the opposite valve opened to act as an outflow, the liquor being forced 20 or drawn back through the cops from the outside either by pressure or exhaust through the pipe P . The pipe P can also be used for forcing air through the cops to dry them after dyeing. After the cops have been 25 treated they are removed by simply disconnecting the pipe P and removing the flange or head f^2 .

Fig. 3 shows a method of holding the cops without the use of a central pipe. With this 30 arrangement the cops are placed on a rod r which is provided with suitable centering devices such as the collars h , h , etc. These are preferably of spider form, having a suitable number, three or more, prongs or arms i , 35 which engage the interior of the coils c and locate the rod centrally within the openings of the cops. A flange e having a central opening e^2 , arranged opposite the opening of the inlet pipe j , abuts one end of the end 40 cop A and a second flange e^3 is adapted to be pressed against the end of the opposite cop of the series, being adjusted along the rod by means of the hand nut k . The rod r is preferably secured at r^2 in the pipe j . 45 With this arrangement the dyeing liquor is pumped in through the pipe j , circulates through the interior of the cops, and is forced radially outward into the yarn mass. It will be seen that the purpose of having 50 the collars h of skeleton form, is to prevent them from closing the openings through the cops and obstructing the passage of the liquor.

In Fig. 4 is shown still another method of 55 holding the cops. Two flanges l and l^2 are provided, and these are adapted to be drawn together by the rods m , m , etc., which pass through holes arranged around the outside of the flanges. The flanges are drawn together 60 by adjusting the hand nuts n , n , etc., and the rods m , m serve to keep the cops in alinement. The liquor is forced into the central opening through the cops from the pipe O which is screwed into an opening 65 in the flange l .

It will be seen that our invention consists of a method of treating yarn in cops or packages of considerable bulk in dyeing or similar processes, to provide for improved results and economical handling.

While we have shown the preferred means for applying our process we do not herein claim the apparatus, but

What we do claim is;

1. The within described improvement in 75 preparing yarn for treatment with fluids, the same consisting in winding the yarn into hollow cops longitudinally compressible throughout the mass of material, then arranging a plurality of such cops axially in 80 line with their ends in contact and forcing them longitudinally together while mechanically maintaining the opening through the center of the cops, and confining them under end pressure to secure a uniform 85 density of the entire mass.

2. The within described process of treating a column of yarn wound in package form with a central opening, the parts of 90 said column differing in density, consisting in applying end pressure until all parts of said column are of uniform density, mechanically maintaining the central opening through said column during compression without interfering with said compression, 95 and passing a fluid through said compressed yarn.

3. The within described process of treating 100 yarn wound in packages compressible throughout and varying in density consisting in arranging a plurality of such packages axially in line, applying end pressure until all parts of said line are of uniform density, mechanically maintaining a central opening through said packages during compression without interfering with said compression, and passing a fluid through said compressed packages.

4. The within described process of treating 110 yarn the same consisting in winding the yarn in hollow packages longitudinally compressible throughout, arranging a plurality of such packages axially in line, applying end pressure to secure a uniform density of the entire mass of material, and then passing a fluid radially through the mass.

5. An improved process of treating yarn, 115 consisting of winding the yarn on porous tubes adapted to be longitudinally contracted; arranging a series of cops with their ends abutting and the tubes alining; applying pressure to the ends of the end cops to contract the tubes and compress the yarn into a continuous tubular mass; and forcing fluid through the mass.

6. The herein described improvement in 120 treating yarn wound in hollow packages longitudinally compressible throughout, consisting in supporting a plurality of such packages with their ends abutting and their 125

130

openings alining while mechanically maintaining a continuous central opening throughout the series of packages without interfering with their compressibility, applying pressure to the end packages to compress the entire mass longitudinally to secure a uniform density throughout, closing one end of the opening in the mass and then forcing fluid into the other end of the opening under pressure.

7. The herein described process of treating yarn wound in hollow packages longitudinally compressible throughout, consisting in arranging a series of such packages with their ends abutting and their openings alining while mechanically maintaining the opening throughout the series of packages without interfering with their compressibility, compressing the packages longitudinally to secure a uniform density throughout the mass, forcing the liquid into the central

opening under pressure to cause it to pass radially through the mass, and forcing a gas through the mass to dry the yarn.

8. The within described improvement in preparing yarn for treatment with fluids, the same consisting in winding the yarn on a longitudinally compressible pervious holder to form a mass longitudinally compressible throughout its whole length, applying pressure to the ends of the mass to secure a uniform density throughout its whole length, and then passing the fluid radially through the mass.

In testimony whereof we affix our signatures in presence of two witnesses.
